The ornamental design for a hacksaw blade, as shown and described.

DESCRIPTION

FIG. 1 is a front view of a hacksaw blade showing the present invention, where the back view is a mirror image thereof; FIG. 2 is a top view of the hacksaw blade of FIG. 1; FIG. 3 is a bottom view of the hacksaw blade of FIG. 1; FIG. 4 is a left side view of the hacksaw blade of FIG. 1, shown at an enlarged scale; and, FIG. 5 is a right side view of the hacksaw blade of FIG. 1, shown at an enlarged scale.

The broken lines in the drawings show structure or boundaries that are not part of the claimed design, but rather show portions of the article in which the design is embodied or applied to that are not considered part of the claimed design.
